UNITED STATES PATENT OFFICE.

CHAUNCEY L. C. MAGEE, OF CHICAGO, ILLINOIS.

FURNACE GRATE.

Application filed February 5, 1923. Serial No. 616,909.

This invention relates to furnace grates of the kind shown and described in application Serial No. 586,331 filed September 5, 1922, and is in the nature of an improvement 5 thereon.

Generally stated, the object of the improvements constituting the present invention is to provide means whereby ashes may be accumulated at each end of each compartment formed below the upper portion of the traveling grate, as well as at the front and rear sides of each compartment, so that the chain grate will drag on an accumulation of ashes entirely surrounding the top or 10 open upper end of each compartment, thereby sealing the compartments at their ends as well as their front and rear sides, by the permanent accumulation of ashes which engages the under side of the upper portion 15 of the traveling grate.

It is also an object to provide certain details and features of construction tending to increase the general efficiency and the desirability of a furnace grate structure of 20 this particular character.

To these and other useful ends the invention consists in matters hereinafter set forth and claimed and shown in the accompanying drawings in which—

25 Figure 1 is a longitudinal section of a chain grate furnace construction embodying the principles of the invention.

Figure 2 is an enlarged transverse section on line 2—2 in Figure 4.

30 Figure 3 is a detail section on line 3—3 in Figure 4.

Figure 4 is a plan of the furnace grate structure, showing the upper portion of the chain grate fuel support broken away or removed to show the construction of the air 35 compartments and other elements below.

As thus illustrated, the invention comprises a furnace 1 of masonry of any suitable or desired character. The coal is fed 40 into the furnace by a hopper 2, or by any suitable means. There is an ash pit 3 and a bridge wall 4, with space 5 immediately below the bridge wall to receive the clinkers and spent fuel.

45 The chain grate structure comprises transverse metal beams 6, 7, 8 and 9 having longitudinal rails 10 supported thereon. The chain grate 11 may be of any suitable or desired character, and slides on top of the rails 10, as shown, to support the fuel in position 50 for combustion in the furnace. The lower

portion of the chain grate rides on the rails 12 which are supported by transverse members 13 below. The transverse members are supported by the longitudinal side frames 14 of the grate structure, which latter are in turn supported by wheels 15 resting on the stationary rails 16 arranged in the masonry at the opposite sides of the furnace. In this way the entire grate structure can 60 be pulled out of the furnace when such is necessary or desirable.

To provide a supply of air to the burning fuel, in a way permitting full control thereof, so that the air can be supplied to one section of the grate and shut off from another section, in order to ensure proper combustion of the fuel, transverse air chambers or compartments 17, 18 and 19 are provided, immediately below the upper stretch or portion of 70 the belt like chain grate. To form these chambers or compartments transverse sheet metal members 20 and 21 are provided, each member being formed with a flat top wall and integral and sloping side walls as shown. 75 The transverse sheet metal members 22 and 23 co-operate with the transverse beams 8 and 9 to form the other sides of the compartments or chambers 17 and 19 in the manner shown; but the chamber or compartment 18 is formed between the sheet metal members 20 and 21 and the air passes up 80 through the three compartments or chambers and through the burning fuel carried by the chain grate. Sliding plates 24, 25 and 26 85 serve as dampers for the lower ends or beams of the compartments 17, 18 and 19, respectively, and are controlled through the medium of rods 27 connected to the hand levers 28 at the front of the furnace. Thus 90 any compartment or chamber can be opened at its bottom, to allow the air to pass upwardly, and to dump the ashes or pieces of fuel which may fall from the grate. It will 95 be seen, however, that four accumulations of ashes 29, 30, 31 and 32 are formed on top of the members 22, 20, 21 and 23, respectively, plates 33 being fixed on the sides of the hollow transverse members to keep the 100 chain grate from displacing these accumulations of ashes in a forward direction. In this way, the compartments or air chambers 17, 18 and 19 are sealed at their sides, so 105 to speak, by the ashes which engage the under surface of the chain grate, so that air cannot pass up through one compartment and cross over into another compartment.

95

100

105

110

The ends of these air chambers or compartments are closed by the longitudinal frame members 34, which latter have their ends supported by the transverse frame members 8 and 9, as shown, and plates 35 rest on these members on the side frames 14 to form a support for ashes 36 at each end of each air compartment or chamber, so that the top of each air compartment or chamber is entirely surrounded by a deposit or accumulation of ashes engaging the lower surface of the upper stretch of the chain grate. Consequently, when air passes up into the compartment 18, for example, the air cannot pass longitudinally into either of the other two compartments, under the grate, and cannot pass out at either end of this compartment, but is compelled to pass upwardly through the grate and through the fuel thereon.

The hollow transverse members 22, 20, 21 and 23 form spaces between the air compartments or chambers and the dampers 24, 25 and 26, when opened, occupy positions immediately below these spaces or substantially within these spaces, in the manner shown. Each damper is adapted to slide out of its space and into position to close the bottom of the air compartment or chamber, and each damper when thus closed will catch and hold any ashes or pieces of fuel which fall from the grate, but the damper when opened will dump the accumulation and cause it to fall downward.

It will also be seen that a plate 37 is supported on the transverse beams 6 and 7, so that the siftings or screenings from the coal will form an accumulation 38 upon this plate to prevent air from passing upward through the grate at this point. Between the beams 7 and 8 the air is always free to pass upwardly between the grate and the fuel thereon, but beyond the accumulation 39 of ashes the supply of air to the burning fuel is subject to sectional regulation, so that air can be supplied at one point and shut off at another point at will, whereby certain theories regarding the burning of different kinds of fuel may be carried out. A sheet metal baffle plate 39 is adjustably secured to the beam 9 to rest upon the lower portion of the belt like chain grate, and is of a length and is so arranged that air passing upwardly from below the grate structure cannot pass up between the beam 9 and the wheels or sprockets 40 at the inner end of the grate structure. With further respect to the controlling of the air in this way, a support 41 is placed on the innermost beam 13 to ensure an accumulation of ashes 42 in position to engage the bottom of the chain grate, whereby air cannot pass upwardly from the pit 3 and then into the space 43 in the bridge wall. In other words, the air supply below the grate structure must pass up through the upper portion of the grate at four places

only, to-wit:—Between the beams 7 and 8, or through the chamber 17, or through the chamber 18, or through the chamber 19, but at all other points the air is effectively shut off and is prevented from escaping upwardly into the combustion chamber. The fuel is fed from the hopper 2 on to the grate, and the latter is operated by any suitable means to carry the fuel gradually forward, and the speed of travel is so regulated that the fuel is spent and completely burned by the time it reaches the inner end of the grate structure. The different accumulations of ashes really become a part of the grate structure, as they form the means for shutting off the air here and there wherever such is necessary or desirable. Other means might be employed, or other substances, but the ashes which fall from the grate cost nothing and serve the purpose very well.

Thus the transverse accumulations of ashes form ash seals between the chain grate and the stationary structure below, in such a manner that broken or dragging links will not break anything, for each accumulation is readily displaceable, as these accumulations are not restrained laterally, and can easily be pushed off by anything dragging on the under side of the upper stretch of the belt forming the grate. If the stationary structure below were too close, broken or dragging links would catch and make trouble, and for this reason it is impracticable to have the stationary structure rub on the bottom of the upper stretch of the belt forming the chain grate; but by forming and arranging the stationary structure some distance below, thus providing ample space between the upper stretch of the grate and the top surface of the stationary structure below, providing wide supports upon which ashes can accumulate, sealing means can be formed between the air compartments which will effectively prevent passage of the air from one compartment to the other, but which will at the same time be adapted to permit free movement of any broken or dragging links or other parts which may hang down from the upper stretch of the belt forming the chain grate. At the sides of the grate, of course, other accumulations of ashes are formed on the stationary structure, to rub against the side edges of the belt like structure forming the grate, whereby a seal is provided at each side of the grate between the side edges thereof and the stationary structure.

It will be seen that the plates 35 are supported by the longitudinal frame members 34, which latter support the transverse hollow partitions previously described. The plates 44 are secured to the upper portions of the longitudinal side portions 14 of the stoker structure, and are located in the upper portions of the spaces 45 formed between the

brickwork 1 and the outer sides of the members 14, in the manner shown. These plates 44, therefore, extend above the plates 3, and, in conjunction with the T-beams 46 set into the masonry as shown, form lateral ash cavities for the ash seals 36 previously described. In this way, air might pass upwardly in the spaces 45, but is prevented from so doing by the ash seals 36, and in this way no air can pass upwardly into these spaces and then into the compartments 17, 18 and 19 previously described. Hence the air can only enter these compartments at the bottom of these compartments, and the sliding plates have absolute control of the supply of air to the under side of the fuel above these compartments.

Looking at Fig. 2 of the drawings, it will be seen that a longitudinal air space is provided beneath each plate 35, formed between the beams 14 and 34 at each side of the grate structure, so that each longitudinal ash seal 36 is formed immediately above a longitudinal air space, and whereby the transverse air compartments are of less length than the width of the grate, so that the longitudinal ash seals unite the ends of the transverse ash seals. In this way, a rectangular frame-like ash seal is provided, in one and the same plane, having transverse slots therein formed between the hollow partitions. Thus the ash seals 36 engage the lower edges of the T-irons 46, and the entire grate structure can be pushed in and out of the furnace structure, in a manner that will be readily understood, with both the transverse and the longitudinal ash seals undisturbed on top thereof.

With the construction shown and described, and with the entire stoker supported by wheels 15 on the rail 16, it is obvious that the entire stoker can be pulled out with all of the ash seals intact, for cleaning or inspection or repair. The ash seals 29, 30, 31 and 32, and the lateral ash seals 36 and 38 can obviously be formed while the stoker is outside of the furnace, so that the stoker will be ready to work in the desired manner as soon as it is pushed in between the furnace walls, and without waiting for dropping ashes to gradually form the ash seals. Of course, the dropping ashes can be depended upon to renew the ash seals if they should be disturbed or knocked off by the operation of the grate, but when the stoker is pulled out of the furnace all parts thereof, including the elements 35, 44, 33 and 34, and the associated elements, can be inspected and repaired and cleaned. When the stoker is pushed back into the furnace, all of the elements thereof, including the elements forming the various ash seals, are automatically brought into the exact relation necessary to form the ash seals and control the draft in the manner described, and in a manner to

70 seal the spaces between the sides of the stoker and the furnace walls at certain points, as shown and described, in order to confine the updraft of the air through the fuel to the air compartments between the different transverse ash seals, and between the two lateral or side ash seals 36, in the manner shown and described. Of course, inasmuch as the ash seal 38, and perhaps the ash seal 29, are not exactly in a position to be formed by 75 dropping ashes, being below the fresh fuel, it is obvious that these ash seals can be advantageously formed upon their supports before the stoker is pushed into the furnace.

What I claim as my invention is—
80

1. A stoker structure comprising a continuous chain grate, a series of partitions in the space beneath the upper part of said grate, dividing said space into a series of compartments, a longitudinal ash support 85 spaced a distance below each side edge of the upper portion of the grate, extending a distance under the grate, being flat on top and adapted to support ashes thereon to co-operate with the side edges of said grate to seal the ends of said compartments, furnace walls spaced a distance from the side edges of the upper portion of the grate, forming spaces to feed ashes onto said longitudinal ash supports, said partitions lying some distance beneath the bottom of said upper part, and being flat on top and adapted to support ashes on their top portions in the same plane as said first mentioned ashes to co-operate with said upper part to prevent passage of air from one compartment to the next, each partition being hollow and of less length than the width of the grate, the opposite ends of each partition terminating at the inner edges of said longitudinal ash supports, so that the side edges of the grate overhang the ends of said partition, and a member 90 slideable into position beneath said partition and slideable therefrom to close the bottom of a compartment whereby the passage of air through said compartment may be controlled, the structure having means forming a longitudinal air space below each longitudinal ash support, between the outer sides of the structure and the ends of the partitions, said longitudinal ash supports forming baffle plates to prevent upward passage of air from said longitudinal air spaces, the stoker having means to support the said partitions and longitudinal members and whereby the opposite ends of said compartments are closed against communication with said longitudinal air spaces.
95

2. A stoker comprising a continuous chain grate, a series of partitions in the space beneath the upper part of said grate, dividing said space into a series of compartments, a longitudinal ash support spaced a distance below each side edge of the upper portion of the grate, extending a distance under the 100
105
110

130

grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, said partitions being flat on top and adapted to support ashes on their top portions to cooperate with said upper part to prevent passage of air from one compartment to the next, each partition being hollow and of less length than the width of the grate, the opposite ends of each partition terminating at the inner edges of said longitudinal ash supports, so that the side edges of the grate overhang the ends of said partitions, and having means at its opposite ends to support said longitudinal ash supports, a member 100 slidable into position beneath said partition and slidale therefrom to close the bottom of a compartment, whereby the passage of air through said compartment may be controlled, and means operable from the front of said stoker for shifting said member, the structure having means forming a longitudinal air space below each side edge of the upper portion of the grate, extending a distance under the grate, being flat on top and adapted to support ashes thereon to cooperate with the side edges of said grate to seal the ends of said compartments, said partitions lying some distance beneath the bottom of said upper part, and being flat on top and adapted to support ashes on their top portions to cooperate with said upper part to prevent passage of air from one compartment to the next, longitudinal frame members engaging the ends of said partitions and forming supports for said longitudinal ash supports, so that all of the ashes are in the same plane, and a member slidale into position beneath said partition and slidale therefrom to close the bottom of a compartment whereby the passage of air through said compartment may be controlled, each partition having its opposite ends set in a distance under the grate and being wider than said slidale member so as to permit the latter to be withdrawn thereunder, the structure having means forming a longitudinal air space below each longitudinal ash support, between the outer sides of said longitudinal frame members and the inner sides of the stoker side portions, the stoker having means to support the said partitions and longitudinal members and whereby the opposite ends of said compartments are closed against communication with said longitudinal air spaces.

3. A stoker comprising a continuous chain grate, a series of partitions in the space beneath the upper part of said grate, dividing said space into a series of compartments, a longitudinal ash support spaced a distance below each side of the upper portion of the grate, extending a distance under the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, said partitions being flat on top and adapted to support ashes on their top portions to cooperate with said chain grate to prevent passage of air from one compartment to the next, each partition being hollow and of less length than the width of the grate, the opposite ends of each partition terminating at the inner edges of said longitudinal ash supports, so that the side edges of the grate overhang the ends of said partitions, and having its opposite ends closed by longitudinal members that also form supports for said longitudinal ash supports, a member slidale into position beneath said partition and slid-

able therefrom to close the bottom of a compartment, whereby the passage of air through said compartment may be controlled, and a lever operable from the front of said stoker for shifting said member, the structure having means forming a longitudinal air space below each longitudinal ash support between the outer sides of the structure and the ends of the partitions, said longitudinal ash supports forming baffle plates to prevent upward passage of air from said longitudinal air spaces, the stoker having means to support the said partitions and longitudinal members and whereby the opposite ends of said compartments are closed against communication with said longitudinal air spaces.

4. A stoker comprising a continuous chain grate, a series of partitions in the space beneath the upper part of said grate, dividing said space into a series of compartments, a longitudinal ash support spaced a distance below each side edge of the upper portion of the grate, extending a distance under the grate, being flat on top and adapted to support ashes thereon to cooperate with the side edges of said grate to seal the ends of said compartments, said partitions lying some distance beneath the bottom of said upper part, and being flat on top and adapted to support ashes on their top portions to cooperate with said upper part to prevent passage of air from one compartment to the next, longitudinal frame members engaging the ends of said partitions and forming supports for said longitudinal ash supports, so that all of the ashes are in the same plane, and a member slidale into position beneath said partition and slidale therefrom to close the bottom of a compartment whereby the passage of air through said compartment may be controlled, each partition having its opposite ends set in a distance under the grate and being wider than said slidale member so as to permit the latter to be withdrawn thereunder, the structure having means forming a longitudinal air space below each longitudinal ash support, between the outer sides of said longitudinal frame members and the inner sides of the stoker side portions, the stoker having means to support the said partitions and longitudinal members and whereby the opposite ends of said compartments are closed against communication with said longitudinal air spaces.

5. A stoker comprising a continuous chain grate, a series of partitions in the space beneath the upper part of said grate, dividing said space into a series of compartments, a longitudinal ash support spaced a distance below each side of the upper portion of the grate, extending a distance under the grate, being flat on top and adapted to support ashes thereon to cooperate with the side edges of said grate to seal the ends of said compartments, furnace walls spaced a dis-

- tance from the side edges of the upper portion of the grate, forming spaces to feed ashes onto said longitudinal ash supports, said partitions lying some distance beneath the bottom of said upper part, and being flat on top and adapted to support ashes on their top portions to cooperate with said upper part to prevent passage of air from one compartment to the next, means forming an ash cavity at the outer side of each longitudinal ash support, and a horizontally disposed member slidable into position beneath said partition and slidable therefrom to close the bottom of a compartment whereby the passage of air through said compartment may be controlled, each partition having its opposite ends set in a distance under the grate and being wider than said slidable member so as to permit the latter to be withdrawn thereunder, that edge of said partition under which the slidable member moves lying closely adjacent thereto so as to scrape off any ash accumulated thereon as said slid-
 able member is retracted, the structure having means forming a longitudinal air space below each longitudinal ash support, between the outer sides of the structure and the ends of the partitions, said longitudinal ash supports forming baffle plates to prevent upward passage of air from said longitudinal air spaces, the stoker having means to support the said partitions and longitudinal members and whereby the opposite ends of said compartments are closed against communication with said longitudinal air spaces.
6. A stoker comprising a continuous chain grate, a series of partitions in the space beneath the upper part of said grate, dividing said space into a series of compartments, a longitudinal ash support spaced a distance below each side of the upper portion of the grate, extending a distance under the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, said partitions having their opposite ends set in a distance under the grate and lying some distance beneath the bottom of said upper part, and being flat on top and adapted to support ashes on their top portions to cooperate with said upper part to prevent passage of air from one compartment to the next, means for supporting said longitudinal ash supports in position to support the ashes thereon in the same plane as the ashes on said partition, so that the entire ash seal is integral and rectangular and has transverse openings forming the tops of said compartments, and a member slidable into position beneath said partition and slidable therefrom to close the bottom of a compartment whereby the passage of air through said compartment may be controlled, each partition being wider than said slidable member so as to permit the latter to be withdrawn thereunder, that edge of said partition under which the slidable member moves lying closely adjacent thereto so as to scrape off any ash accumulated thereon as said slid-
 able member is retracted, and means forming a vertical space at each side of the stoker structure, whereby air might pass upwardly in each vertical space and into said compartments, but in which said upward passage of air is prevented by the ashes which accumulate in said ash cavity at each side of the grate, the structure having means forming a longitudinal air space below each longitudinal ash support, between the outer sides of the structure and the ends of the partitions, said longitudinal ash supports forming baffle plates to prevent upward passage of air from said longitudinal air spaces.

the stoker having means to support the said partitions and longitudinal members and whereby the opposite ends of said compartments are closed against communication with said longitudinal air spaces.

8. A stoker comprising a continuous chain grate, a series of partitions in the space beneath the upper part of said grate, dividing said space into a series of compartments, a longitudinal ash support spaced a distance below each side edge of the upper portion of the grate, extending a distance under the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, said partitions having their opposite ends set in a distance under the grate and lying some distance beneath the bottom of said upper part, and being flat on top and adapted to support ashes on their top portions to cooperate with said upper part to prevent passage of air from one compartment to the next, means for supporting said longitudinal ash supports in position to support the ashes thereon in the same plane as the ashes on said partition, so that the entire ash seal is integral and rectangular and has transverse openings forming the tops of said compartments, and a member slidable into position beneath said partition and slidable therefrom to close the bottom of a compartment whereby the passage of air through said compartment may be controlled, said slidable member being adapted when closed to catch ashes sifting through the upper part of said grate to further seal the same, and means forming a vertical air space at each side of the stoker structure, whereby air might pass upwardly in each vertical space and into said compartments, but which upward passage of the air is prevented by the ashes which accumulate on the longitudinal ash support below each side edge of the grate, the structure having means forming a longitudinal air space below each longitudinal ash support, between the outer sides of the structure and the ends of the partitions, said longitudinal ash supports forming baffle plates to prevent upward passage of air from said longitudinal air spaces, the stoker having means to support the said partitions and longitudinal members and whereby the opposite ends of said compartments are closed against communication with said longitudinal air spaces.

9. A stoker structure comprising a continuous chain grate, a series of partitions in the space beneath the upper part of said grate, dividing said space into a series of compartments, a longitudinal ash support spaced a distance below each side edge of the

upper portion of the grate, being flat on top and adapted to support ashes thereon to cooperate with the side edges of said grate to seal the ends of said compartments, longitudinal frame members forming the sides of the structure, means forming an air space at the outer side of each frame member, means to prevent the ashes from falling into said air spaces, at each side of the structure, and means fixed on the furnace walls and engaging the top of each longitudinal ash seal to prevent air from rising at each side of the grate from said air spaces, said partitions lying some distance beneath the bottom of said upper part, and being flat on top and adapted to support ashes on their top portions in the same plane as said first mentioned ashes to cooperate with said upper part to prevent passage of air from one compartment to the next, each partition being hollow, and a member slidable into position beneath said partition and slidable therefrom to close the bottom of a compartment whereby the passage of air through said compartment may be controlled, in combination with means whereby the entire stoker is movable bodily out of the furnace with said accumulations of ashes in place and is also movable into the furnace with said longitudinal ash supports in operative relation to said fixed ash engaging means on the furnace walls.

10. A stoker structure comprising a continuous chain grate, a series of partitions in the space beneath the upper part of said grate, dividing said space into a series of compartments, a longitudinal ash support spaced a distance below each side edge of the upper portion of the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, longitudinal frame members forming the sides of the structure, means forming an air space at the outer sides of each frame member, means to prevent the ashes from falling into said air spaces, at each side of the structure, and means fixed on the furnace walls and engaging the top of each longitudinal ash seal to prevent air from rising at each side of the grate from said air spaces, said partitions being flat on top and adapted to support ashes on their top portions to cooperate with said upper part to prevent passage of air from one compartment to the next, each partition being hollow, and having means at its opposite ends to support said longitudinal ash supports, a member slidable into position beneath said partition and slidable therefrom to close the bottom of a compartment, whereby the passage of air through

said compartment may be controlled, and means operable from the front of said stoker for shifting said member, in combination with means whereby the entire 5 stoker is movable bodily out of the furnace with said accumulations of ashes in place and is also movable into the furnace with said longitudinal ash supports in operative relation to said fixed ash engaging means on the furnace walls.

11. A stoker structure comprising a continuous chain grate, a series of partitions in the space beneath the upper part of said grate, dividing said space into a series of compartments, a longitudinal ash support spaced a distance below each side of the upper portion of the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, longitudinal frame members forming the sides of the structure, means forming an air space at the outer side of each frame member, means to prevent the ashes from falling into said air spaces, at each side of the structure, and means fixed on the furnace walls and engaging the top of each longitudinal ash seal to prevent air from rising at each side of the grate from said air spaces, said partitions lying some distance beneath the bottom of said upper part, and being flat on top and adapted to support ashes on their top portions to cooperate with said upper part to prevent passage of air from one compartment to the next, longitudinal members engaging the ends of said partitions and forming supports for said longitudinal ash supports, so that all of the ashes are in the same plane, and a member slidably into position beneath said partition and slidably therefrom to close the bottom of a compartment whereby the passage of air through said compartment may be controlled, each partition being wider than said slidable member so as to permit the latter to be withdrawn thereunder, in combination with means whereby the entire stoker is movable bodily out of the furnace with said accumulations of ashes in place and is also movable into the furnace with said longitudinal ash supports in operative relation to said fixed ash engaging means on the furnace walls.
13. A stoker structure comprising a continuous chain grate, a series of partitions in the space beneath the upper part of said grate, dividing said space into a series of compartments, a longitudinal ash support spaced a distance below each side of the upper portion of the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, longitudinal frame members forming the sides of the structure, means forming an air space at the outer side of each frame member, means to prevent the ashes from falling into said air spaces, at each side of the structure, and means fixed on the furnace walls and engaging the top of each longitudinal ash seal to prevent air from rising at each side of the grate from said air spaces, said partitions lying some distance beneath the bottom of said upper part, and being flat on top and adapted to support ashes on their top portions to cooperate with said upper part to prevent passage of air from one compartment to the next, each partition being hollow, and having its opposite ends closed by longitudinal members that also form supports for said longitudinal ash supports, a member slidably into position beneath said partition and slidably therefrom to close the bottom of a compartment, whereby the passage of air through said compartment may be controlled, and a lever operable from the front of said stoker for shifting said member, in combination with means whereby the entire stoker is movable bodily out of the furnace with said accumulations of ashes in place and is also movable into the furnace with said longitudinal ash supports in operative relation to said fixed ash engaging means on the furnace walls.
12. A stoker structure comprising a continuous chain grate, a series of partitions in the space beneath the upper part of said grate, dividing said space into a series of compartments, a longitudinal ash support spaced a distance below each side edge of the upper portion of the grate, being flat on top and adapted to support ashes thereon to cooperate with the side edges of said grate to seal the ends of said compartments, furnace walls spaced a distance from the side edges of the upper portion of the grate,

forming spaces to feed ashes onto said longitudinal ash supports, longitudinal frame members forming the sides of the structure, means forming an air space at the outer side of each frame member, means to prevent the ashes from falling into said air spaces, at each side of the structure, and means fixed on the furnace walls and engaging the top of each longitudinal ash seal to prevent air from rising at each side of the grate from said air spaces, said partitions lying some distance beneath the bottom of said upper part, and being flat on top and adapted to support ashes on their top portions to cooperate with said upper part to prevent passage of air from one compartment to the next, longitudinal members engaging the ends of said partitions and forming supports for said longitudinal ash supports, so that all of the ashes are in the same plane, and a member slidably into position beneath said partition and slidably therefrom to close the bottom of a compartment whereby the passage of air through said compartment may be controlled, each partition being wider than said slidable member so as to permit the latter to be withdrawn thereunder, in combination with means whereby the entire stoker is movable bodily out of the furnace with said accumulations of ashes in place and is also movable into the furnace with said longitudinal ash supports in operative relation to said fixed ash engaging means on the furnace walls.

13. A stoker structure comprising a continuous chain grate, a series of partitions in the space beneath the upper part of said grate, dividing said space into a series of compartments, a longitudinal ash support spaced a distance below each side of the upper portion of the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, longitudinal frame members forming the sides of the structure, means forming an air space at the outer side of each frame member, means to prevent the ashes from falling into said air spaces, at each side of the structure, and means fixed on the furnace walls and engaging the top of each longitudinal ash seal to prevent air from rising at each side of the grate from said air spaces, said partitions lying some distance beneath the bottom of said upper part, and being flat on top and adapted to support ashes on their top portions to cooperate with said upper part to prevent passage of air from one compartment to the next, means forming an ash cavity at the outer side of each longitudinal ash support,

and a horizontally disposed member slidable into position beneath said partition and slid-
able therefrom to close the bottom of a com-
partment whereby the passage of air through
said compartment may be controlled, each
partition being wider than said slidable
member so as to permit the latter to be with-
drawn thereunder, that edge of said partition
under which the slidable member moves
10 lying closely adjacent thereto so as to scrape
off any ash accumulated thereon as said slid-
able member is retracted, in combination
with means whereby the entire stoker is
movable bodily out of the furnace with said
15 accumulations of ashes in place and is also
movable into the furnace with said longitudi-
nal ash supports in operative relation
to said fixed ash engaging means on the fur-
nace walls.

20 14. A stoker structure comprising a con-
tinuous chain grate, a series of partitions in
the space beneath the upper part of said
grate, dividing said space into a series of
25 compartments, a longitudinal ash support
spaced a distance below each side edge of
the upper portion of the grate, being flat on
top and adapted to support ashes thereon to
cooperate with the side edges of said grate
30 to seal the ends of said compartments, fur-
nace walls spaced a distance from the side
edges of the upper portion of the grate,
forming spaces to feed ashes onto said longi-
tudinal ash supports, longitudinal frame
35 members forming the sides of the structure,
means forming an air space at the outer side
of each frame member, means to prevent the
ashes from falling into said air spaces, at
each side of the structure, and means fixed
40 on the furnace walls and engaging the top
of each longitudinal ash seal to prevent air
from rising at each side of the grate from
said air spaces, said partitions lying some
distance beneath the bottom of said upper
45 part, and being flat on top and adapted to
support ashes on their top portions to coop-
erate with said upper part to prevent pas-
sage of air from one compartment to the
next, means for supporting said longitudi-
50 nal ash supports in position to support the
ashes thereon in the same plane as the ashes
on said partition, so that the entire ash seal
is integral and rectangular and has trans-
verse openings forming the tops of said com-
55 partments, and a member slidable into posi-
tion beneath said partition and slidable
therefrom to close the bottom of a comp-
artment whereby the passage of air through
said compartment may be controlled, said
60 slidable member being adapted when closed
to catch ashes sifting through the upper part
of said grate to further seal the same, in
combination with means whereby the entire
stoker is movable bodily out of the furnace
65 with said accumulations of ashes in place
and is also movable into the furnace with

said longitudinal ash supports in operative
relation to said fixed ash engaging means
on the furnace walls.

15. A stoker structure comprising a con-
tinuous chain grate, a series of partitions in
the space beneath the upper part of said
grate, dividing said space into a series of
compartments, a longitudinal ash support
70 spaced a distance below each side of the up-
per portion of the grate, being flat on top
and adapted to support ashes thereon to co-
operate with the side edges of said grate to
seal the ends of said compartments, furnace
75 walls spaced a distance from the side edges
of the upper portion of the grate, forming
80 spaces to feed ashes onto said longitudinal
ash supports, longitudinal frame members
forming the sides of the structure, means
forming an air space at the outer side of each
frame member, means to prevent the ashes
85 from falling into said air spaces, at each side
of the structure, and means fixed on the fur-
nace walls and engaging the top of each
longitudinal ash seal to prevent air from
90 rising at each side of the grate from said air
spaces, said partitions lying some distance
beneath the bottom of said upper part, and
being flat on top and adapted to support
ashes on their top portions to cooperate with
95 said upper part to prevent passage of air
from one compartment to the next, means
forming an ash cavity at the outer side of
each longitudinal ash support, and a hori-
zontally disposed member slidable into posi-
100 tion beneath said partition and slidable
therefrom to close the bottom of a comp-
artment whereby the passage of air through
said compartment may be controlled, each
partition being wider than said slidable
105 member so as to permit the latter to be with-
drawn thereunder, that edge of said partition
under which the slidable member moves
lying closely adjacent thereto so as to scrape
off any ash accumulated thereon as said
110 slidable member is retracted, and means for-
ming a vertical space at each side of the
stoker structure, whereby air might pass
upwardly in each vertical space and into said
compartments, but in which said upward
115 passage of air is prevented by the ashes which
accumulate in said ash cavity at each side
of the grate, in combination with means
whereby the entire stoker is movable bodily
out of the furnace with said accumulations
120 of ashes in place and is also movable into
the furnace with said longitudinal ash sup-
ports in operative relation to said fixed ash
engaging means on the furnace walls.

16. A stoker structure comprising a con-
tinuous chain grate, a series of partitions in
the space beneath the upper part of said grate,
dividing said space into a series of com-
partments, a longitudinal ash support spaced
125 a distance below each side edge of the up-
per portion of the grate, being flat on top
130

and adapted to support ashes thereon to co-operate with the side edges of said grate to seal the ends of said compartments, furnace walls spaced a distance from the side edges 5 of the upper portion of the grate, forming spaces to feed ashes onto said longitudinal ash supports, longitudinal frame members forming the sides of the structure, means forming an air space at the outer side of each 10 frame member, means to prevent the ashes from falling into said air spaces, at each side of the structure, and means fixed on the furnace walls and engaging the top of each longitudinal ash seal to prevent air from rising 15 at each side of the grate from said air spaces, said partitions lying some distance beneath the bottom of said upper part, and being flat on top and adapted to support ashes on their top portions to cooperate with 20 said upper part to prevent passage of air from one compartment to the next, means for supporting said longitudinal ash supports in position to support the ashes thereon 25 in the same plane as the ashes on said partition, so that the entire ash seal is integral and rectangular and has transverse openings forming the tops of said compartments, and a member slidable into position beneath said partition and slidable therefrom to close the 30 bottom of a compartment whereby the passage of air through said compartment may be controlled, said slidable member being adapted when closed to catch ashes sifting through the upper part of said grate to further seal the same, and means forming a 35 vertical air space at each side of the stoker structure, whereby air might pass upwardly in each vertical space and into said compartments, but which upward passage of the air is prevented by the ashes which 40 accumulate on the longitudinal ash support below each side edge of the grate, in combination with means whereby the entire stoker is movable bodily out of the furnace 45 with said accumulations of ashes in place and is also movable into the furnace with said longitudinal ash supports in operative relation to said fixed ash engaging means on the furnace walls.

50 17. A stoker comprising a continuous chain grate, a series of partitions in the space beneath the upper part of said grate, dividing said space into a series of compartments, a longitudinal ash support spaced a distance 55 below each side edge of the upper portion of the grate, being flat on top and adapted to support ashes thereon to cooperate with the side edges of said grate to seal the ends of said compartments, furnace walls spaced a 60 distance from the side edges of the upper portion of the grate, forming spaces to feed ashes onto said longitudinal ash supports, means forming air spaces at opposite sides of the stoker, between the outer sides of the 65 stoker and the inner sides of the furnace

walls, upstanding means to prevent the ashes on said longitudinal supports from falling into said air spaces, spaced outwardly a distance from the side edges of the upper portion of the grate, said partitions lying 70 some distance beneath the bottom of said upper part, and being flat on top and adapted to support ashes on their top portions in the same plane as said first mentioned ashes to cooperate with said upper part to 75 prevent passage of air from one compartment to the next, rails to support the upper part of the grate a distance above said partitions and longitudinal ash supports, upstanding means on the edge of one or more 80 of said partitions between said rails to prevent the ashes thereon from falling into said compartments, each partition being hollow, and a member slidable into position beneath said partition and slidable therefrom 85 to close the bottom of a compartment whereby the passage of air through said compartment may be controlled.

18. A stoker comprising a continuous chain grate, a series of partitions in the space 90 beneath the upper part of said grate, dividing said space into a series of compartments, a longitudinal ash support spaced a distance below each side edge of the upper portion of the grate, being flat on top and adapted 95 to support ashes thereon to cooperate with the side edges of said grate to seal the ends of said compartments, furnace walls spaced a distance from the side edges of the upper portion of the grate, forming spaces to feed 100 ashes onto said longitudinal ash supports, means forming air spaces at opposite sides of the stoker, between the outer sides of the furnace walls, upstanding means to prevent the ashes on said longitudinal supports from falling 105 into said air spaces, spaced outwardly a distance from the side edges of the upper part of the grate, said partitions being flat on top and adapted to support ashes on their 110 top portions to cooperate with said upper part to prevent passage of air from one compartment to the next, rails to support the upper part of the grate a distance above said partitions and longitudinal ash supports, 115 upstanding means on the edge of one or more of said partitions between said rails to prevent the ashes thereon from falling into said compartments, each partition being hollow, and having means at its opposite ends to support said longitudinal ash supports, a member slidable into position beneath said partition and slidable therefrom to close the bottom of a compartment, whereby the passage of air through said compartment may be controlled, and means operable from the front of said stoker for shifting said member.

19. A stoker comprising a continuous chain grate, a series of partitions in the space be- 120 125 130

neath the upper part of said grate, dividing said space into a series of compartments, a longitudinal ash support spaced a distance below each side of the upper portion of the 5 grate, being flat on top and adapted to support ashes thereon to cooperate with the side edges of said grate to seal the ends of said compartments, furnace walls spaced a distance from the side edges of the upper portion 10 of the grate, forming spaces to feed ashes onto said longitudinal ash supports, means forming air spaces at opposite sides of the stoker, between the outer sides of the stoker and the inner sides of the furnace 15 walls, upstanding means to prevent the ashes on said longitudinal supports from falling into said air spaces, spaced outwardly a distance from the side edges of the upper part of the grate, said partitions being flat 20 on top and adapted to support ashes on their top portions to cooperate with said chain grate to prevent passage of air from one compartment to the next, rails to support the upper part of the grate a distance above 25 said partitions and longitudinal ash supports, upstanding means on the edge of one or more of said partitions between said rails to prevent the ashes thereon from falling into said compartments, each partition being 30 hollow, and having its opposite ends closed by longitudinal members that also form supports for said longitudinal ash supports, a member 35 slidable into position beneath said partition and slidable therefrom to close the bottom of a compartment, whereby the passage of air through said compartment may be controlled, and a lever operable from the front of said stoker for shifting said member.

40 20. A stoker comprising a continuous chain grate, a series of partitions in the space beneath the upper part of said grate, dividing said space into a series of compartments, a longitudinal ash support spaced a distance 45 below each side edge of the upper portion of the grate, being flat on top and adapted to support ashes thereon to cooperate with the side edges of said grate to seal the ends of said compartments, furnace walls spaced a distance from the side edges of the upper portion of the grate, forming spaces to feed ashes onto said longitudinal ash supports, means forming air spaces at opposite sides of the stoker, between the outer sides of the stoker and the inner sides of the furnace walls, upstanding means to 50 prevent the ashes on said longitudinal supports from falling into said air spaces, spaced outwardly a distance from the side edges of the upper part of the grate, said partitions lying some distance beneath the bottom of said upper part, and being flat 55 on top and adapted to support ashes on their top portions to cooperate with said upper part to prevent passage of air from one compartment to the next, rails to support the upper part of the grate a distance above said partitions and longitudinal ash supports, upstanding means on the edge of one or more of said partitions between said rails to prevent the 60 ashes thereon from falling into said compartments, means forming an ash cavity at the outer side of each longitudinal ash support, and a horizontally disposed member 65 slidable into position beneath said partition and slidable therefrom to close the bottom of a compartment whereby the passage of air through said compartment may be controlled, each partition being wider than said 70 slidable member so as to permit the latter to be withdrawn thereunder, that edge of said partition under which the slidable member moves lying closely adjacent thereto so as to scrape off any ash accumulated thereon as said slidable member is retracted.

75 65 22. A stoker comprising a continuous 80

support the upper part of the grate a distance above said partitions and longitudinal ash supports, upstanding means on the edge of one or more of said partitions between said rails to prevent the ashes thereon from falling into said compartments, longitudinal members engaging the ends of said partitions and forming supports for said longitudinal ash supports, so that all of the ashes are in the same plane, and a member slidable 75 into position beneath said partition and slidable therefrom to close the bottom of a compartment whereby the passage of air through said compartment may be controlled, each partition being wider than said slidable member so as to permit the latter to be withdrawn thereunder.

21. A stoker comprising a continuous chain grate, a series of partitions in the space beneath the upper part of said grate, dividing said space into a series of compartments, a longitudinal ash support spaced a distance below each side of the upper portion of the grate, being flat on top and adapted to support ashes thereon to 85 cooperate with the side edges of said grate to seal the ends of said compartments, furnace walls spaced a distance from the side edges of the upper portion of the grate, forming 90 spaces to feed ashes onto said longitudinal ash supports, means forming air spaces at opposite sides of the stoker, between the outer sides of the stoker and the inner sides of the furnace walls, upstanding means to prevent the ashes on said longitudinal supports from falling into said air spaces, spaced outwardly a distance from the side edges of the upper part of the grate, said partitions lying some distance beneath the 95 bottom of said upper part, and being flat 100 on top and adapted to support ashes on their top portions to cooperate with said upper part to prevent passage of air from one compartment to the next, rails to support the upper part of the grate a distance above said partitions and longitudinal ash supports, upstanding means on the edge of one or more of said partitions between said rails to prevent the 105 ashes thereon from falling into said compartments, means forming an ash cavity at the outer side of each longitudinal ash support, and a horizontally disposed member 110 slidable into position beneath said partition and slidable therefrom to close the bottom of a compartment whereby the passage of air through said compartment may be controlled, each partition being wider than said 115 slidable member so as to permit the latter to be withdrawn thereunder, that edge of said partition under which the slidable member moves lying closely adjacent thereto so as to scrape off any ash accumulated thereon as said slidable member is retracted.

120 125 130 22. A stoker comprising a continuous

chain grate, a series of partitions in the space beneath the upper part of said grate, dividing said space into a series of compartments, a longitudinal ash support spaced 5 a distance below each side edge of the upper portion of the grate, being flat on top and adapted to support ashes thereon to cooperate with the side edges of said grate to seal the ends of said compartments, furnace walls 10 spaced a distance from the side edges of the upper portion of the grate, forming spaces to feed ashes onto said longitudinal ash supports, means forming air spaces at opposite sides of the stoker, between the outer sides 15 of the stoker and the inner sides of the furnace walls, upstanding means to prevent the ashes on said longitudinal supports from falling into said air spaces, spaced outwardly a distance from the side edges of the upper 20 part of the grate, said partitions lying some distance beneath the bottom of said upper part, and being flat on top and adapted to support ashes on their top portions to cooperate with said upper part to prevent passage of air from one compartment to the next, rails 25 to support the upper part of the grate a distance above said partitions and longitudinal ash supports, upstanding means on the edge of one or more of said partitions 30 between said rails to prevent the ashes thereon from falling into said compartments, means forming an ash cavity at the outer side of each longitudinal ash support, and a horizontally disposed member slidable into 35 position beneath said partition and slidable therefrom to close the bottom of a compartment whereby the passage of air through said compartment may be controlled, each partition being wider than said slidable 40 member so as to permit the latter to be withdrawn thereunder, that edge of said partition under which the slidable member moves lying closely adjacent thereto so as to scrape off any ash accumulated thereon as said slid 45 able member is retracted, and means forming a vertical space at each side of the stoker structure, whereby air might pass upwardly in each vertical space and into said compartments, but in which said upward passage of air is prevented by the ashes which accumulate in said ash cavity at each side of the 50 grate.

24. A stoker comprising a continuous chain grate, a series of partitions in the space beneath the upper part of said grate, dividing said space into a series of compartments, a longitudinal ash support spaced 55 a distance below each side edge of the upper portion of the grate, being flat on top and adapted to support ashes thereon to cooperate with the side edges of said grate to seal the ends of said compartments, furnace walls spaced a distance from the side edges of the upper 60 portion of the grate, forming spaces to feed ashes onto said longitudinal ash supports, means forming air spaces at opposite sides of the stoker, between the outer sides of the stoker and the inner sides of the furnace walls, upstanding means to prevent the ashes 65 on said longitudinal supports from falling into said air spaces, spaced outwardly a distance from the side edges of the upper part of the grate, said partitions lying some distance beneath the bottom of said upper part, and being flat on top and adapted to support ashes on their top portions to cooperate with said upper part to prevent passage of air from one compartment to the next, rails to support the upper part of the grate a distance above said partitions and longitudinal ash supports, upstanding means on the edge of one or more of said partitions between 70 said rails to prevent the ashes thereon from falling into said compartment, means for 75

23. A stoker comprising a continuous chain grate, a series of partitions in the space beneath the upper part of said grate, dividing said space into a series of compartments, a longitudinal ash support spaced 75 a distance below each side of the upper portion of the grate, being flat on top and adapted to support ashes thereon to cooperate with the side edges of said grate to seal the ends of said compartments, furnace walls spaced a distance from the side edges of the upper 80 portion of the grate, forming spaces to feed ashes onto said longitudinal ash supports, means forming air spaces at opposite sides of the stoker, between the outer sides of the stoker and the inner sides of the furnace walls, upstanding means to prevent the ashes 85 on said longitudinal supports from falling into said air spaces, spaced outwardly a distance from the side edges of the upper part of the grate, said partitions lying some distance beneath the bottom of said upper part, and being flat on top and adapted to support ashes on their top portions to cooperate with said upper part to prevent passage of air from one compartment to the next, rails to support the upper part of the grate a distance above said partitions and longitudinal ash supports, upstanding means on the edge of one or more of said partitions between 90 said rails to prevent the ashes thereon from falling into said compartment, means for 95

supporting said longitudinal ash supports in position to support the ashes thereon in the same plane as the ashes on said partition, so that the entire ash seal is integral and rectangular and has transverse openings forming the tops of said compartments, and a member slidable into position beneath said partition and slidable therefrom to close the bottom of a compartment whereby the passage of air through said compartment may be controlled, said slidable member being

adapted when closed to catch ashes sifting through the upper part of said grate to further seal the same, and means forming a vertical air space at each side of the stoker structure, whereby air might pass upwardly in each vertical space and into said compartments, but which upward passage of the air is prevented by the ashes which accumulate on the longitudinal ash support below each side edge of the grate.

CHAUNCEY L. C. MAGEE.
